UNITED STATES PATENT OFFICE.

MARGUERITE ROGERS, OF CAMBRIDGE, MASSACHUSETTS, ASSIGNOR, BY MESNE ASSIGNMENTS, TO THE BUTEAU SALES COMPANY, INCORPORATED, OF NEW YORK, N. Y., A CORPORATION OF NEW YORK.

DESIGN FOR A DOLL.

60,373.

Specification for Design.

Patented Feb. 7, 1922.

Application filed July 6, 1921. Serial No. 482,853. Term of patent 14 years.

To all whom it may concern:

Be it known that I, MARGUERITE ROGERS, a citizen of the United States, residing at Cambridge, in the county of Middlesex and State of Massachusetts, have invented a new, original, and ornamental Design for Dolls, of which the following is a specification, reference being had to the accompanying drawing, forming part thereof.

Fig. 1 is a front elevational view of the upper body portion and head of a doll embodying my new design, and

Fig. 2 is a side elevational view of the upper body portion and head.

I claim:

The ornamental design for a doll as shown.
MARGUERITE ROGERS.
